[57] ABSTRACT

A hinge exhibitor for apprising prospective users of the hinge's structure and operation includes a demonstration hinge mounted to simulate an application of the hinge. Messages appearing on the hinge leaves are explanatory of hinge components that may be seen through transparent hinge knuckles.

HINGE EXHIBITOR

BACKGROUND OF THE INVENTION

This invention relates to a hinge exhibitor which is suitable for use in the promotion and sale of all types of hinges.

Various methods have been used in the past to demonstrate improvements in new hinge structures. One technique has been to disassemble an actual hinge device and then exhibit and explain each part separately while reassembling the hinge. While this procedure is adequate for relatively simple hinges, it does not suffice to illustrate adequately the structure and operation of a fully assembled complex hinge mechanism. Another technique has been to use a "cutaway" metal hinge which, as the name implies, reveals portions of the interior construction within the bore of the hinge knuckles by cutting away sections of the outer casing. It is apparent that this technique does not provide full visibility of the interior hinge structure and, moreover, does not convey to the viewer the pleasing impression desired for demonstration purposes. The structure and advantages of a hinge can only be appreciated by observing a fully assembled and intact working model in a simulated application of the hinge which shows the interrelated functions of all the hinge elements. Such a working model or exhibitor has been heretofore unknown.

Accordingly, it is an object of the present invention to provide a hinge exhibitor suitable for use as a sales aid which demonstrates and explains the hinge's interior mechanism while the hinge is fully assembled.

It is another object of the invention to facilitate the demonstration of a hinge by making its interior components visible and providing messages juxtaposed to such components and explanatory of the hinge.

It is a further object of the present invention to provide a hinge exhibitor which may be adapted to demonstrate any type of hinge and which is compact, attractive and economical to produce.

BRIEF SUMMARY OF THE INVENTION

These and other objects of the present invention are accomplished by providing a demonstration hinge having transparent exterior components which contain interior components, thereby revealing the construction and function of the hinge mechanism. In a preferred embodiment of the invention, hinge leaves are provided with backing plates in such a manner that operation of the hinge is facilitated with the hinge knuckles exposed to full view when the hinge leaves are together and 180° apart. Messages explaining the details of the revealed hinge construction appear at the hinge leaves in juxtaposition to the appropriate hinge components. Such messages may be applied directly upon the hinge leaves, upon an opaque sheet or member beneath transparent hinge leaves, or upon a separate transparent plastic sheet beneath transparent hinge leaves. In the latter instance, a background film, on which a metallized reflective surface has preferably been deposited, may be positioned beneath the transparent plastic sheet to provide a surface that enhances the visibility of the explanatory messages. The reflective surface may also suggest the material of the actual hinge. The hinge and, if used, the sheet or sheets beneath the hinge leaves, are secured to the backing plates by mounting screws.

To provide an especially attractive and realistic hinge exhibitor, the backing plates may take the form of mounting blocks made of finished wood. The hinge leaves are inserted into correspondingly-shaped mortises formed in the mounting blocks, which simulate the door and jamb mortises actually used with the hinge, to simulate an actual application of the hinge. The interior hinge mechanism within a bore formed by the hinge knuckles, and the mounting screws, may be made from the actual hinge production components, while the outer casing of the hinge is molded from a suitable transparent plastic.

BRIEF DESCRIPTION OF THE DRAWINGS

In the accompanying drawings:

FIG. 1 is a front elevational view of a typical hinge exhibitor in closed position with the hinge leaves together arranged according to the present position;

5 FIG. 2 is a front elevational view of the hinge exhibitor assembly of FIG. 1 in an open position with the hinge leaves 180° apart;

10 FIG. 3 is a cross-sectional view of the transparent knuckle which reveals the interior construction of the demonstration hinge taken along line 3-3 of FIG. 1, looking in the direction of the arrows; and

15 FIG. 4 is a cross-sectional view of the leaf showing a typical arrangement for displaying explanatory messages in juxtaposition to various hinge components taken along line 4-4 of FIG. 2, looking in the direction of the arrows.

DESCRIPTION OF THE PREFERRED EMBODIMENT

In the illustrative embodiment of the invention shown in FIGS. 1 and 2, a hinge exhibitor 10 comprises a three-knuckle 20 demonstration hinge 11 which is secured to a mounting 12 by means of hinge mounting screws 13-20. The mounting 12 is formed by backing plates 21 and 22 preferably constructed of wood and shown here in the form of mounting blocks. As best seen in FIGS. 2, 3 and 4, the interior surfaces 23 and 24 of the

25 mounting blocks are provided with hinge mortises 25 and 26, respectively, with suitably spaced screw holes in the base 27 of each mortise (mortise 26 in FIG. 4 being illustrative) for receiving the mounting screws 13-20 of hinge leaves 28 and 29 of the hinge 11. Integral with the leaf 28 is a single knuckle

30 30 positioned between a pair of spaced-apart knuckles 31 and 32 integral with the leaf 29. The knuckles 30-32 are constructed so that when aligned in operating position a bore 33 is formed. The hinge knuckles 30-32 are formed of any suitable

35 type of transparent material. For example, the transparent plastic polycarbonate has been found satisfactory. The hinge leaves 28 and 29 may also be formed of the same transparent plastic and, if desired, molded integrally with the knuckles. The transparency of the knuckles reveals interior components

40 34 of the hinge within the bore 33 of the knuckles 30-32, as shown in FIG. 3.

As best seen in FIG. 4, the base 27 of the mortise 26 in the mounting block 22 receives a background sheet 35 formed, for example, of a plastic material such as Mylar or cellulose acetate having a metallized reflective surface that simulates the material of the actual manufactured hinge. Between the background sheet and the transparent leaf 29 is positioned a transparent message sheet 36 formed, for example, of cellulose acetate to which has been applied display messages explanatory of the hinge. As shown in FIG. 2, written messages 37-41 on the sheets, juxtaposed to the hinge knuckles explain the details of the revealed construction 34 within the knuckle bore 33. The sheets 35 and 36 are provided with suitably spaced screw holes to receive the mounting screws 13-20 which retain the parts in position.

If desired, the messages may be applied directly on the hinge leaves 28 and 29. If the leaves are transparent, the readability of the messages may be improved by making the under surfaces of the hinge leaves reflective by metallizing them.

The messages can also be applied directly on the metallized reflective surfaces of the sheets 35 or, alternatively, the sheets 35 may be opaque and carry the explanatory messages.

65 When the hinge exhibitor 10 is properly assembled, the knuckles 30-32, which reveal the interior components 34 within the knuckle bore 33, are continually exposed to view, as seen in FIGS. 1 and 2, when the hinge is opened and closed to simulate the actual mounting of the hinge on a door and

70 jamb. This is accomplished by having the edges 42 and 43 of the leaves 28 and 29, respectively, jutting out from the mortises 25 and 26 of the block members 21 and 22, respectively. With the hinge open, the messages explain the hinge components to which they are juxtaposed. This facilitates the demonstration of the hinge to prospective users.

The inventive hinge exhibitor greatly facilitates the demonstration of a hinge. Thus, prospective buyers and users who view the explanatory messages, and operate the hinge in a mounting simulating an application of the hinge, are quickly apprised of the structure and advantages of the hinge.

I claim:

1. A hinge exhibitor comprising two mounting blocks, a mounting surface on one side of each block, a demonstration hinge having transparent leaves and transparent knuckles, said leaves being received by the mounting surfaces on the mounting blocks to simulate actual mounting of the hinge, said knuckles when aligned forming a bore containing an interior

mechanism of the hinge, a mirrorlike background sheet providing a reflective surface between each of the transparent leaves and the mounting surfaces, means providing messages between each of the reflective surfaces and the transparent hinge leaves, at least some of the messages being juxtaposed to portions of the hinge described by the messages, the reflective surfaces enhancing the visibility of the messages, and means fastening the leaves to the mounting blocks to enable operation of the hinge by movement of the blocks with the knuckles exposed to view when the hinge leaves are together and when the hinge leaves are 180° apart.
